(57) **CLAIM**

The ornamental design for a floor mopping sheet, as shown and described.

DESCRIPTION

FIG. 1 is a perspective view of a floor mopping sheet according to our new design;

FIG. 2 is a top view of the sheet of FIG. 1, the bottom view being identical thereto;

FIG. 3 is a right side elevation view of the sheet of FIG. 1, the left side being a mirror image thereto;

FIG. 4 is a rear view of the sheet of FIG. 1; and,

FIG. 5 is a front view of the sheet of FIG. 1.

The features shown in broken lines are for environmental purposes only and form no part of the claimed design.

1 Claim, 1 Drawing Sheet
